[57] CLAIM

The ornamental design for a combined mouse and rat trap, as shown and described.

DESCRIPTION

FIG. 1 is a perspective view of a mouse and rat trap showing my new design;

FIG. 2 is a top plan view thereof;

FIG. 3 is a left side elevational view, the right side being a mirror image thereof;

FIG. 4 is a bottom plan view thereof;

FIG. 5 is a front elevational view thereof; and

FIG. 6 is a rear elevational view thereof.

FIG.1.

FIG. 2.

FIG. 3.

FIG.4.

FIG.5.

FIG.6.
